YARN SUPPORT

Carl Epps, Rome, Ga., assignor to Tubize Chatillion Corporation, a corporation of Delaware

Application February 24, 1934, Serial No. 712,748

3 Claims. (Cl. 242—130)

This invention relates to yarn supports and has for its object certain improvements in the structure of yarn supports. The invention relates more particularly to improvements in adjustable multiple position brackets for supporting wound yarn.

In the manufacture of yarns from strands and the like the material is customarily wound on a cone, bobbin, cop or similar device. Cone winding, for example, is widely employed in the manufacture of artificial silk yarn. The yarn is wound on tapered or conical shaped pasteboard or paper tubes. The cones of yarn are subsequently unwound in the making of textile fabrics. In the manufacture of hosiery, for example, the coned yarn is unwound directly to a knitting machine.

Special devices are employed to unwind the yarn. The coned yarn must be appropriately supported in order that it may be conveniently and efficiently unwound and passed to a knitting machine, or whatever device is employed to receive and fabricate the yarn. A number of difficulties are encountered. The devices employed to support the yarn may not be readily adaptable to the particular knitting machine employed. It may be inconvenient to place a new cone of yarn, for example, in position for unwinding. Also, the coned yarn may be unwound under non-uniform conditions of tension, which frequently results in the formation of knots or kinks in the moving yarn, and causes a lack of uniformity in the knitted fabric.

As a result of my investigations I have developed a yarn support that largely avoids the difficulties just mentioned. The support is readily adjustable to a great number of different positions that adapts it to be employed in conjunction with almost any type of knitting machine or other device to receive unwinding yarn. Means are provided in association with the adjustable support for varying and controlling the tension under which yarn is unwound.

The improvement briefly contemplates at least a four-link adjustable position bracket, the first link in the series being a base adapted to support a spindle. At least one of the intermediate links is adapted to be securely fastened to an auxiliary support, such as a knitting machine. The last link is a ballooning link provided with a yarn guide. A tension device is preferably mounted on the ballooning link to steady the unwinding yarn. Means are present for tightening the links or joints to hold the bracket in fixed position.

These and other features of the invention will be more apparent on considering the attached

drawings, taken in conjunction with the following description, in which:

Fig. 1 is a side elevation of an adjustable bracket of the invention, showing a cone of yarn mounted in a vertical position for unwinding upwardly;

Fig. 2 is a plan view of Fig. 1;

Figs. 3, 4 and 5 are side elevations of the adjustable bracket, showing cones of yarn mounted in various inclined positions for unwinding.

Fig. 6 is a side elevation of the tension device in one mode of application.

The adjustable multiple position bracket shown comprises a base link 10, two intermediate links 11 and 12 and a frame or ballooning link 13 connected in series. Tightening means, such as thumb screws 14, 15 and 16 are provided at the pivoted joints of the links, respectively.

The base link is provided with a spindle 17, attachable at or near the exterior end of the link by means of a threaded nut 18, which is adapted to receive a cone of yarn 19 mounted on a tapered paper cone 20. Means are advantageously provided on the spindle for gripping the interior of the paper cone, to prevent it from turning and to hold it securely for the unwinding of the yarn. The cone gripping means employed may, for example, be of the improved type disclosed in my copending application Serial No. 712,747, filed February 24, 1934.

In order to facilitate the unwinding of the yarn, the base link is also advantageously provided with a frame or yarn supporting device 21. This device may be cylindrical in contour, an elastic fabric yarn support 22 on which the yarn itself may rest being stretched at least in part across the same. The fabric is drawn taut around the perimeter of the supporting device, and is clamped to the side thereof by means of a ring member 23 made adjustable by means of a tension spring 24. A circular opening 25 is provided by the fabric for the insertion both of the spindle 17 and the lower end of the paper cone 20 extending beyond the base of the coned yarn itself. This pad support may, for example, be of the type disclosed and claimed in my copending application Serial No. 712,746, filed February 24, 1934.

Both intermediate links 11 and 12 are provided with threaded holes 26 and 27, respectively, which are adapted to receive a complementary support member 28. This support member may in turn be secured to the ultimate support 29 for the entire bracket structure; for example, a knitting machine. Means other than threaded holes 26 and 27 may of course be associated with the intermediate links 11 and 12 for fastening purposes.

It will be clear from the construction shown that either or both of the intermediate links may be employed to support the entire bracket.

The ballooning link 13 is provided with a yarn guide 30 of conventional design, such as a porcelain eyelet. The ballooning link is also preferably provided with a tension device 31 of suitable construction. Figs. 1, 2 and 3 illustrate a tension device in combination with the bracket in accordance with the invention. It comprises an extension member 32 securable to the ballooning link by means of a screw 33 extending therethrough. The upper end of the extension member is provided with a lateral arm 34 securable by means of a threaded screw 35. The lateral arm is in turn provided with a yarn guide 36; such as a porcelain eyelet, preferably smaller than the porcelain eyelet 30. It will be seen from the construction illustrated that the porcelain eyelets 30 and 36 may be placed in co-axial alignment, or deviated from such an alignment to any extent desired simply by rotating the extension member 32 on the ballooning link 13; or by shifting the position of the lateral arm 34. In this manner any desired operating tension may be placed on yarn 37 as it is unwound from the cone 19 to, for example, the knitting machine. If reference is made to Fig. 2, it will be seen that the lateral link 34 has been moved sidewise so that the porcelain guide eyes 30 and 36 are off-center, which places the unwinding yarn under tension.

The yarn may be placed under additional tension by winding it around the member 32, as shown in Fig. 6, with the guide 36 in the position illustrated or in any other desired position with respect to the guide 30.

The cone of yarn 19 shown in Fig. 1 is in a vertical position for unwinding. Inspection of Figs. 3, 4 and 5 shows the coned yarn in various inclined positions for unwinding. In the case of Fig. 3, the coned yarn is supported in a lateral position, inclined upwardly, the unwinding yarn being passed through the tension device. Fig. 4 likewise shows the coned yarn in a lateral position, inclined upwardly, but the tension device is not employed, the unwinding yarn merely being passed through the porcelain eyelet 30 in the ballooning link 13. In the case of Fig. 5, the coned yarn is supported in a lateral and downwardly inclined position, the unwinding yarn being passed merely through the yarn guide in the ballooning link.

A comparison of Figs. 1, 3, 4 and 5 will show the adjustable bracket placed in various positions, both with respect to ultimate support as well as unwinding. In the case of Fig. 1 the bracket is supported through intermediate link 11 to an inclined support 29 adjacent the bracket. Fig. 3 shows the bracket supported through intermediate link 11 onto ultimate support 29 in a horizontal position below the bracket. Fig. 4 shows the bracket depending through intermediate link 12 to the ultimate support 29 above the bracket. In the case of Fig. 5, the bracket is supported through intermediate link 12 to ultimate support 29 placed below the bracket.

In operation the bracket is fastened at some convenient place on or in close proximity to the

knitting machine, or other device to receive the yarn; which is done through intermediate link 11 or 12, or both. The remaining links are then adjusted and locked in a position to permit unwinding of the yarn. Care is of course taken to locate the base link and the ballooning link opposite one another in such a way as to make it easy for an operator to place a new cone of yarn on the spindle from time to time. To this end it is ordinarily only necessary to loosen the ballooning link, move it out of the way, and insert a new cone on the spindle; the base link thus always remaining rigidly locked to intermediate link 11. The ballooning link is then returned to its operating position and fastened by means of thumb screw 16. After threading the guide porcelain eyelet 30, the cone of yarn is ready for unwinding. In case use is to be made of the tension device 31, the yarn is likewise threaded through porcelain eyelet 36. The unwinding yarn may then be placed under appropriate tension by moving the lateral arm 34. It will be seen that the device of the invention offers a number of desirable improvements in the operation of unwinding yarn.

I claim:

1. The improvement in a yarn support comprising a four-link adjustable position bracket, the first link in the series being a base adapted to support a spindle, at least one of the second and third intermediate links being adapted to be securely fastened to an auxiliary support, the fourth being a ballooning link provided with a yarn guide, a tension device formed by an extension member secured to the ballooning link,

35 the upper end of the extension member being provided with a movable lateral arm containing a second yarn guide and means for tightening the links at their joints to hold the bracket in fixed position.

2. The improvement in a yarn support comprising a bracket provided with at least four connecting links adjustable in substantially the same plane, the first link in the series being a base adapted to support a spindle, at least one of the second and third intermediate links being adapted to be securely fastened to an auxiliary support, the fourth being a ballooning link provided with a yarn guide, a tension device formed by an extension member secured to the ballooning link,

45 the upper end of the extension member being provided with a movable lateral arm containing a second yarn guide and means for tightening the links at their joints to hold the bracket in fixed position.

3. A yarn support comprising an adjustable-position link bracket having a supporting link securable to an auxiliary support, a link at one side of said supporting link adapted to support a spindle, a ballooning link at the other side of said supporting bracket, all of said links being adjustably connected and capable of swinging in substantially the same horizontal plane, a yarn guide carried by the ballooning link, a tension device carried by the ballooning link, said tension device also including a yarn guide, and the yarn guide of the tension device being located further from the supporting link than the yarn guide of the ballooning link.
